UNITED STATES PATENT OFFICE.

PETER BLATT, OF ALLEGHENY, PENNSYLVANIA.

DUMPING-WAGON.

No. 863,566.

Specification of Letters Patent.

Patented Aug. 13, 1907.

Application filed October 5, 1906. Serial No. 337,573.

To all whom it may concern:

Be it known that I, PETER BLATT, a citizen of the United States of America, residing at Allegheny, in the county of Allegheny and State of Pennsylvania, have 5 invented certain new and useful Improvements in Dumping-Wagons, of which the following is a specification, reference being had therein to the accompanying drawings.

This invention relates to dumping wagons, and it is 10 designed as an improvement on the wagon shown and described in United States Letters Patent No. 799,588, granted to me under date of September 12, 1905.

In the wagon shown in the patent above referred to, the bottom thereof consists of two hinged doors, and 15 novel means are provided for opening and closing said doors.

The present invention aims to provide improved means for operating the hinged doors of the wagon whereby one door closes slightly in advance of the 20 other, to insure a close and snug closing of the doors without liability of clogging the space between the meeting edges of the doors.

The construction of the improvement will be fully described hereinafter, in connection with the accompanying drawing which forms a part of the specification, and its novel features will be defined in the appended claims.

In the drawing: Figure 1 is a side elevation of a dumping-wagon constructed in accordance with the invention; Fig. 2 is a bottom plan view thereof; Fig. 3 is an elevation of the front end of the wagon; Fig. 4 is a similar view of the rear end thereof, and Fig. 5 is a detail elevation of the mechanism for controlling the winding and unwinding of the cable or chain employed.

35 The wagon body comprises oppositely-inclined side boards 1, and inclined end boards 2, said boards forming a hopper-shaped body. To each of the sides 1, at the lower edge thereof is secured by hinges 3, a door 4 and 5.

40 The inner edge of one door is provided with a longitudinal cleat 6 adapted to overlap the confronting edge of the other door when the doors are closed. The doors on their underneath sides, near each end, and adjacent their meeting edges, carry brackets 10, in which are 45 journaled pulleys 7 and 9 serving as sheaves for the respective strands or portions of the chain or cable.

Upon the front end board 2 are secured brackets 11, within which is journaled a shaft 12, one part 13, of 50 which is of greater diameter than the other portion 14, of said shaft. To the enlarged part of the shaft 12, is attached one end of a cable or chain, as shown at the point 15, and said cable passes down under the pulley 7 at the front end of the door 4, thence along underneath said door and under pulley 7 at the rear end thereof, 55 thence upward over a pulley 16^a, down under pulley 16' and over pulley 16 all journaled in a bracket 17,

secured upon the rear end board 2. The cable then passes down under the pulleys 9, carried by the door 5, thence upward over a pulley 18, journaled upon the front end board 2, then under another pulley 19, also 60 journaled upon the front end board, thence upward to the smaller end of the shaft 12, where it is secured as shown. Any equivalent guide may be substituted for the pulleys 18 and 19.

To secure the doors in their closed position, and to 65 elevate them when required, I provide a ratchet wheel 21, fixed upon the shaft 12, and an operating lever 22, loosely mounted upon the shaft 12, adjacent to the ratchet wheel, and provided with a pivoted pawl 23, adapted to engage the teeth of the ratchet wheel, and 70 provided with a weighted arm 24.

Secured upon the front end board adjacent to the ratchet wheel 21, is a bracket 25, in which is journaled a V-shaped double pawl 26. The lower arm of this pawl is normally held in engagement with the ratchet 75 wheel by gravity, and said arm is elevated out of engagement by a beveled lug 27 projecting from the operating lever 22, when the lever is moved backward. The doors are held in closed position by the pawls 23 and 26, and when it is desired to release the doors the 80 lever 22, is moved backward causing the lug 27, to engage the upper arm of the double pawl 26, and slightly elevate said pawl, without disengaging the pawl 23, from the ratchet wheel. The engagement of the lug 27 with the upper arm of the pawl 26, causes said arm to strike 85 the pawl 23, thus releasing it from engagement with the ratchet wheel. The further rearward movement of the lever 22, will bring the lug 27, still further under the upper arm of the double pawl, thus releasing the lower arm from the ratchet wheel, when the weight of 90 the load upon the doors will open the doors, the cable unwinding from the shaft.

The mechanism above described for operating the doors is similar to that disclosed in my Patent #799,588, heretofore referred to. I desire it to be understood 95 however, that I do not confine myself in this application to this form of door actuating mechanism, as in my Patent #823,253 of June 12, 1906, for dumping wagons, I show and claim a different form of door operating mechanism which I may and do employ in connection with the form of wagon shown in this application. To close the doors the shaft is rotated by the lever 22, to re-wind the ends of the cable upon said shaft.

It will be obvious from the illustration in Figs. 2 and 105 3 of the drawings, that the door 4 will be drawn up in advance of the door 5, as the portion 13 of the shaft 12, opposite the door 4, upon which the cable winds, is of greater diameter than the portion 14 of the shaft 12, upon which the other end of the cable winds which 110 raises the door 5, and also for the reason that the end of the cable opposite the door 5, is tensioned and slack-

ened by its passage around the pulleys 18 and 19 on the front end board, and around pulleys 16, 16' and 16" on the rear end board of the wagon body. Any equivalent guides may be substituted for the pulleys 16, 16' and 16". These devices for tensioning the portion of the cable opposite the door 5, constitute the distinguishing features of the present invention, over that shown in the patents above referred to; and it will be apparent that the improvement affords simple and effective means for causing one of the doors to close slightly in advance of the other door.

It will be observed that this device is distinguished from that shown in my Patent #823,253, noted above in that I employ in this device a single chain having both ends connected to the winding shaft or drum, and so arranged that a strand of the chain is provided for closing each door, that is, a chain or cable for each door, effecting a more rapid closing of the doors, yet with the tensioning devices shown and described, one door is closed slightly in advance of the other so as to insure the doors being brought to a perfect closed position.

In using the term cable in the description and claims, I desire it to be understood that I use the same as a generic term to cover a rope, wire cable, chain or other flexible connecting element.

What I claim and desire to secure by Letters Patent is:—

1. In a dumping-wagon, the combination with oppositely-disposed hinged doors, of a shaft constituting a winding drum mounted in bearings at the front of the wagon, and having portions of different diameters, a single cable doubled to form two strands and connected at its ends to different diameter portions of said winding-drum, different strands of said cable extending under the differ-

ent doors, pulleys mounted on the front end board of the wagon and over which one strand of said cable extends, and means for operating the winding-drum.

2. In a dumping-wagon, the combination with a hopper provided with hinged doors, of a shaft constituting a winding drum having different diameters and supported in bearings carried by the hopper, a single cable having its ends connected to different diameters of the shaft and doubled to form a strand for each door, means connected to the shaft for operating the latter to wind both strands of the cable thereon, and means comprising guides carried on one end of the hopper and over which one strand of said cable is trained whereby said strand is tensioned as the drum is operated.

3. In a dumping wagon, the combination with a hopper provided with hinged doors, of a shaft journaled in bearings on one end of said hopper, a single cable for operating both doors, said cable having its ends both connected to said shaft, and doubled to form a strand underneath each door, means whereby one strand of said cable is caused to wind on the shaft at a greater rate of speed than the other strand of the cable, and means for tensioning that strand of the cable that travels at the lesser rate of speed.

4. In a dumping wagon, the combination with a hopper provided with hinged doors, of a shaft journaled in bearings at one end of said hopper, a cable doubled to form strands and having both ends connected to said shaft and a strand of said cable extending underneath each door, means whereby one strand of said cable is caused to wind on said shaft at a greater rate of speed than the other strand, and means at each end of the hopper for tensioning that strand of the cable which travels at the lesser rate of speed.

In testimony whereof I affix my signature in the presence of two witnesses.

PETER BLATT.
